UNITED STATES PATENT OFFICE.

IRWIN D. LANDIS, OF SOUTH BEND, INDIANA, ASSIGNOR TO UNIVERSAL CONVEYOR CO., OF SOUTH BEND, INDIANA, A CORPORATION OF INDIANA.

PIVOTAL DUMP BUCKET.

Application filed May 11, 1921. Serial No. 468,661.

To all whom it may concern:

Be it known that I, IRWIN D. LANDIS, a citizen of the United States, residing at South Bend, in the county of St. Joseph and State of Indiana, have invented certain new and useful Improvements in Pivotal Dump Buckets, of which the following is a specification.

The invention relates to pivoted dump buckets preferably of the type used in connection with loading and unloading apparatus, and has for its object to provide a bucket so constructed, that said bucket may be filled by scooping, and then conveyed to a dump pile, lowered into contact with said pile, unlatched and allowed to dump by gravity, and to right itself by gravity after a dumping operation, and relatch.

A further object is to provide a conveying and dumping bucket, which bucket is self-filling, self-dumping, self-righting and self-latching; thereby obviating the use of extra mechanism for unlatching the bucket and also eliminating the use of extra labor.

A further object is to provide a conveying bucket comprising a receptacle pivoted between the vertical arms of a bail, one of said arms having a downwardly extending notched arm, with which notch a pivoted lever carried by the lower side of the bucket cooperates for holding said bucket against pivotal action. Also to provide said arms which extend downwardly with a camming surface, with which camming surface the pivoted lever engages and is cammed into the notch of the arm when the bucket is returning to a horizontal position after a dumping operation.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:—

Figure 1 is a side elevation of the bucket.
Figure 2 is a rear elevation of the bucket.

Referring to the drawings, the numeral 1 designates the bucket, which bucket is supported and pivoted between the arms 3 of the bail 4. The bail 4 is adapted to be at-

tached to any kind of hoisting and traveler mechanism whereby said bucket as a whole may be moved to a point of loading and to a point of dumping. The bucket 1 is provided with pintles 5, which pintles are disposed above the center of the bucket so that said bucket will right itself by gravity. However the bucket is so constructed that when the same is loaded its forward side 6 will contain sufficient additional weight to cause the bucket as a whole to tilt downwardly at its forward end in the direction of the arrow a thereby dumping the material from the bucket on a pile or in any other place desired. After the dumping operation the bucket returns to normal position as shown in Figure 1 by means of gravity incident to the pivotal point of the bucket being above the center thereof. Secured to the underside of the bucket 1 are spaced angle members 7, between the downwardly extending flanges of which is pivoted a transversely disposed latch bar 8. Latch bar 8 has its outer end 9 projecting beyond one side of the bucket 1, and when the bucket 1 is returned to normal position as shown in Figure 1, the end 9 of said latch bar engages the arcuate camming surface 10 of a plate 11 carried by downwardly extending extension 12 of one of the arms 3 of the bail, said plate 11 being provided with a notch 13 for the reception of said keeper bar end 9. When the end 9 of the keeper bar 8 is in the notch 13, it will be seen that when the bucket 1 is filled with material, that even though the capacity of the bucket, forwardly of the pivotal point thereof, is slightly greater than the capacity of the bucket rearwardly of the pivotal point, said latch bar 8 will prevent the bucket from dumping when it is being conveyed to the point of dumping, such for instance as a coal pile. When the bucket 1 has been conveyed to the point of dumping the same is lowered preferably in engagement with the top of the pile of material, which action will cause the plate 14 carried by the rear end 15 of the latch bar 8 to come into engagement with said material and force the end 15 upwardly. The upward movement of the end 15 of the latch bar 8 upon its initial movement will move the end 9 of the latch bar out of the notch 13 of the extension 12 of the arm 3. Just as soon as the end 9 has been moved sufficiently to

clear the plate 11, the bucket 1, the forward end 6 of which contains the greater amount of material, and consequently is the heaviest, will pivot in the direction of the arrow *a*, thereby dumping the material, and as the bucket is raised after a dumping operation, said bucket will right itself as shown in Figure 1, during which righting action the end 9 of the latch bar 8 will come into engagement with a camming surface 10 of the plate 11 and be cammed into engagement with the notch 13, thereby holding the bucket against tilting as it is moved to the loading position.

15 The loading of the bucket may be accomplished in any way desired, such for instance as by scooping the material, disposing the same under a chute, or manually loading the bucket. However, it is obvious that the 20 bucket may be filled by scooping, then conveyed to a point of dumping, lowered into engagement with the stack of material or any other tripping device, allowed to tilt by gravity and dumped. After the dumping 25 operation said bucket righting itself and relatching by gravity. By providing a structure wherein the above operations are accomplished in the matter set forth, it will be seen that the use of labor is reduced to 30 a minimum, and that one man can conduct a loading, conveying and dumping operation. Also that a device is provided which is positive in its operation and one wherein 35 springs, trap doors, or other mechanisms apt to get out of order are eliminated.

The invention having been set forth what is claimed as new and useful is:—

40 1. A conveying and dumping bucket, said bucket comprising a body portion supported and pivoted in a bail, said body portion being pivoted in said bail in such a manner that said bucket will right itself by gravity after a dumping operation, and latching means for maintaining said bucket normally 45 in a righted position, including a lever extending beneath the bucket and adapted to

be tripped to release the bucket upon contact with an object.

2. A conveying and dumping bucket pivoted in a supporting bail, said bucket being 50 so pivoted in said bail that it will tilt under a load carried therein and right itself upon discharge of said load, and latching means for holding said bucket against pivotal action including a trip lever pivoted to the under side of and having a free end extending beneath the bucket.

3. The combination with a bucket pivoted in a supporting bail and between arms of said bail, of means for holding said bucket 60 against pivotal action, said means comprising an extension carried by one of the arms of the bail and terminating adjacent the lower side of the bucket and provided with a notch, a latch lever pivoted below the 65 bucket and having one of its ends extending beyond the side of the bucket and cooperating with the notch in said extension, the inner end of said latch lever being heavier than the outer end thereof and adapted to be engaged by an obstruction for releasing said latch lever.

4. The combination with a bucket pivoted in a supporting bail and between arms of said bail, of means for holding said bucket 75 against pivotal action, said means comprising an extension carried by one of the arms of the bail and terminating adjacent the lower end of the bucket and provided with a notch, a latch lever pivoted to the under 80 side of the bucket and having one of its ends extending beyond the side of the bucket and cooperating with the notch in said extension, a plate carried by the extension and provided with an arcuate camming surface positioned for guiding the latch lever into the notch of the extension, the inner end 85 of said latch lever being heavier than the outer end thereof.

In testimony whereof I affix my signature.

IRWIN D. LANDIS.
